(57) CLAIM

The ornamental design for a sports cup as shown and described.

DESCRIPTION

FIG. 1 is perspective view of a sports cup showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The portions of the sports cup shown in broken lines form no part of the claimed design.

1 Claim, 8 Drawing Sheets
